UNITED STATES PATENT OFFICE.

HARRY H. HIPWELL AND HARRY T. HIPWELL, OF PITTSBURGH, PENNSYLVANIA.

FLASH-LIGHT.

1,149,913.

Specification of Letters Patent. Patented Aug. 10, 1915.

Application filed April 14, 1915. Serial No. 21,333.

To all whom it may concern:

Be it known that we, HARRY H. HIPWELL and HARRY T. HIPWELL, citizens of the United States, residing at N. S. Pittsburgh, in the county of Allegheny, State of Pennsylvania, have invented a new and useful Flash-Light, of which the following is a specification.

The present invention appertains to portable electric flash lights or search lights, and aims to provide certain improvements in devices of that character.

It is the object of the invention to provide a flash light with novel circuit controlling means, whereby the metallic casing serves as a conductor or portion of the circuit, and unique means being provided for closing the circuit through the battery or source of electrical energy, casing, and lamp or bulb.

Another object of the invention is the provision of a flash light casing of such formation that it will be rigid in construction, will properly accommodate the battery or cell, and will also accommodate the switch operating device in a unique manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a side elevation of the improved flash light. Fig. 2 is a longitudinal section thereon taken on the line 2-2 of Fig. 1. Fig. 3 is a cross section taken on the line 3-3 of Fig. 2.

In carrying out the invention, there is provided a tubular or cylindrical casing 1 which is constructed of metal or other material which is a conductor of electrical energy, whereby the casing is utilized as a portion of the circuit. The casing 1 contains a battery or cell 2 which constitutes the source of electrical energy, and which has a central pole 3 at one end. The battery or cell 2 is adapted to be inserted and removed through one end of the casing 1, and a cap 4 is threaded or otherwise detachably engaged upon said end of the casing 1, and has a

spiral spring 5 secured therein which yieldably forces the battery 2 into proper position within the casing, and which also serves to electrically connect the other pole of the battery and the casing. The cap 4 is of metallic or conducting material in order to properly connect the spring 5 and casing 1 electrically.

A reflector 6 is disposed within the other end of the casing 1, the rim or flange 7 of the reflector seating against the said end of the casing, and the reflector being of metal or other conducting material so as to be in electrical connection with the casing. The reflector 6 has a socket 8 for receiving the threaded plug 9 of the lamp or bulb 10, and a lens 11 is seated against the rim of the reflector over the mouth thereof.

A ring or annulus 12 is threaded or otherwise detachably engaged upon the respective end of the casing and has an annular in-turned flange or lip 13 to overlap the lens 11 and clamp the reflector and lens in place against the end of the casing. One terminal of the lamp 10 is in electrical connection with the socket 8 and reflector 6, so that the said terminal of the lamp is continually connected to the casing 1 and respective pole of the battery, while the other insulated terminal 13' of the lamp is utilized as a contact for the co-operation of the switch therewith.

The switch device embodies a diametrical strip 14 terminally secured to opposite sides of the casing 1 between the battery 2 and reflector 6, and a contact strip 15 carried by the strip 14 at that side thereof adjacent the battery.

A strip of insulation 16 is disposed between the strips 14 and 15, and rivets 17 are engaged through the strips 14, 15 and 16 to clamp them together. The pole 3 of the battery normally engages the contact strip 15.

The switch proper embodies a flexible strip or tongue 18 which has one end engaged to one of the the rivets 17 at that side of the strip 14 opposite the strip 15, a strip of insulation 18' being disposed between the strips 18 and 14. The switch also includes a contact strip 19 having one end engaged to the free end of the strip 18, whereby the switch is in the form of the letter V, the switch being designated generally by the numeral 19'. The rivet 17 which engages the strip 18 electrically connects the strip 15 and strip 18, the said strips being insulated from the strip or yoke 14, whereby a short circuit

is avoided. The other or free end of the switch 19' is connected to one end of a switch operating bar or strip 20 disposed within the casing 1 adjacent one side thereof. One end of the strip or yoke 14 is bifurcated, as at 21, for the passage of the bar 20 therethrough, and the free end of the switch 19' or the respective end of the strip 19 is bent angularly, as at 21', and rivets or other securing elements 22 are engaged through the forward end portion of the bar 20 and the angular portion 21' of the switch. A suitable insulating strip or member 23 is disposed between the bar 20 and switch 19' for insulating them one from the other. A suitable insulation 24 is also disposed between the portion 21 of the switch and the rivets 22.

The bar 20 has a finger piece 25 secured thereto adjacent that end of the bar remote from the switch, and the finger piece 25 works in a longitudinal slot 26 provided in the respective side of the casing. Rivets 27 are also engaged through the bar 20 at the opposite sides of the finger piece 25, and are engaged through the plate or strip 28 slideable upon the exterior of the casing, whereby the bar 20 is guided for proper longitudinal movement.

A salient feature of the invention resides in the fact that the casing 1 is provided between its ends with longitudinal instruck ribs or corrugations 29. The slot 26 is disposed between two of the ribs or corrugations 29, and the bar 20 is adapted to be received and guided in the inner longitudinal channel or depression between said ribs or corrugations. The corrugations 29 are of advantage for three reasons. Thus, the corrugations or ribs 29 reinforce or strengthen the casing 1, so that the casing is not liable to be accidentally dented or bent. Furthermore, the instruck ribs or corrugations 29 reduce the internal diameter of the intermediate portion of the casing, whereby the battery or cell 2 will be received snugly between the ribs or corrugations to be held firmly in place within the casing. Again, the two ribs or corrugations 29 between which the bar 20 is disposed will serve to guide the said bar and sufficiently receive said bar so that it will not interfere with the battery or cell.

In use, supposing the parts to be properly assembled, when the switch operating bar or member 20 is moved rearwardly or away from the lamp end of the casing, the strips or arms 18 and 19 of the switch 19' will be moved toward one another, and the contact strip 19 will be moved away from the terminal 13' of the lamp 10. This will open the electrical circuit to extinguish the lamp. When it is desired to light the lamp, the finger piece 25 is moved forwardly and the bar 20 in being moved forwardly will carry the contact strip 19 into engagement with the

terminal 13' of the lamp, the strip 18 providing a flexible connection between the strip 19 and the strip 15 which engages the pole 3 of the battery. The current may then flow from the pole 3 through the strip 15, respective rivet 17, strip 18, strip 19, lamp 10, reflector 6, casing 1 and spring 5 to the other pole of the battery. Since the switch is insulated from the casing and its supporting strip or yoke 14, there is no liability for a short circuit occurring, it also being noted that the switch is insulated from the switch operating bar or member 20.

In view of the foregoing, taken in connection with the drawing, the advantages and attributes of the features of the invention will be obvious to those skilled in the art, without further comment being necessary.

Having thus described the invention, what is claimed as new is:

1. In a flash light, a conductor casing, a battery therein having one pole connected thereto, a lamp carried by the casing and having one terminal electrically connected thereto, an insulated contact carried by the casing for engaging the other pole of the battery, a flexible switch secured to said contact and movable into engagement with the other terminal of the lamp, and means for manually moving the switch from the exterior of the casing.

2. In a flash light, a conductor casing, a battery therein having one pole connected thereto, a lamp carried by the casing and having one terminal electrically connected thereto, an insulated contact carried by the casing for engaging the other pole of the battery, a V-shaped switch having one end secured to said contact and movable into and out of engagement with the other terminal of the lamp, and a manually operable slideable member carried by the casing and secured to the other end of the switch for operating the same.

3. In a flash light, a conductor casing, a battery therein having one pole connected thereto, a lamp carried by the casing and having one terminal electrically connected thereto, a yoke secured within the casing between the battery and lamp, an insulated contact carried by one side of the yoke for the engagement of the other pole of the battery, a longitudinal bar slideable through one end portion of the yoke adjacent one side of the casing, a V-shaped switch having one end connected to said contact and having its other end connected to one end of said bar, the switch being insulated from the casing and being movable into and out of engagement with the other terminal of the lamp, the casing having a longitudinal slot, and a finger piece working in said slot and engaged to said bar adjacent the other end thereof.

4. In a flash light, a tubular casing pro-

vided between its ends with longitudinal in-
struck ribs to reinforce the casing and to
snugly receive a battery therein, the casing
having a longitudinal slot between a pair of
5 the ribs, a longitudinally movable switch
operating member between said pair of ribs,
and a finger piece working in said slot and
engaged to said switch operating member.

In testimony that we claim the foregoing
as our own, we have hereto affixed our sig- 10
natures in the presence of two witnesses.
